WALTER E. MCCOY, OF NEW YORK, N. Y., ASSIGNOR TO WESTINGHOUSE ELECTRIC & MANUFACTURING COMPANY, A CORPORATION OF PENNSYLVANIA.

CIRCUIT INTERRUPTER.

Application filed April 14, 1920. Serial No. 373,907.

My invention relates to latching devices and particularly to means for latching circuit interrupters.

The object of my invention is to provide a device of the above indicated character in which one or more latch members shall be so formed and related to holding and held members that are biased apart with considerable force as to receive only relatively-small component forces of the total latching load, thereby facilitating the releasing operations and requiring only a relatively-small releasing effort.

In practicing my invention, I provide a hollow member having oppositely-disposed openings leading from an intermediate portion thereof in which holding members are disposed and yieldably attached to the hollow member. A bifurcated member, adapted to embrace the hollow member, has portions for positioning opposite the openings to receive the holding members. A resiliently-biased plunger is so formed and of such different diameters as to move the holding members into and out of engagement with the bifurcated member. The holding members are so positioned as to receive only a relatively-small portion of the total latching load and, in turn, are so related to a releasing member as to require a relatively small amount of releasing effort. This facilitates and ensures relatively-quick operation of the interrupter and reduces the amount of wear of the engaging parts.

Figure 1 of the accompanying drawings is a side elevational view of an interrupter embodying my invention, showing the interrupter in its closed position; Figs. 2 and 3 are detail views of the operating mechanism of the interrupter in the open and reset positions, respectively; Fig. 4 is an enlarged detail, side sectional view of a latch mechanism embodying my invention, and Fig. 5 is a view taken along the line V—V of Fig. 4.

A circuit interrupter 1 embodies a tank 2, terminals 3, a bar or beam 4 that supports bridging contact members (not shown) within the tank 2 and a link 5 pivotally connected, at one end, to a bracket 6 on the bar 4 and, at the other end, to a lever 7. The lever 7 is pivoted, by a pin 8, to a bracket 9 that supports the tank 2 and is supported on a switchboard panel 10 or other suitable device. A bell-crank lever 11, having a stop portion 12 for engagement with a lower por-

tion of the bracket 9, is pivotally mounted, by a pin 13, on the bracket 9, and is operatively connected, by a link 14, to the lever 7.

A bifurcated lever 15 is also pivotally mounted on the pin 13 and is disposed on two sides of one arm of the bell-crank lever 11 to constitute therewith a compound operating lever. The levers 11 and 15 both extend through openings in the panel 10 and in a plate or structure 16 supported on the front surface of the panel 10.

Similarly-constructed latching devices 17 and 18 are disposed, respectively, at the outer end of the bell-crank lever 11 and on the upper part of a shell or casing of a tripping magnet 19 disposed at the lower end of the plate 16. The latching device 17 is adapted to latch the levers 11 and 15 together, as shown in Figs. 1 and 3, and the latching device 18 is adapted to hold the lever 15.

Each of the latching devices 17 and 18 comprises a portion 20 having a central bore 21, disposed substantially in the plane of operation of the levers 11 and 15, that is tapered at its lower portion 22 and has an aperture 23 leading therefrom. Oppositely-disposed openings 24 communicate with the central bore 21 at the ends of channels or grooves 25 in the sides of the portion 20. Balls 26, employed as the latching elements in the latching devices 17 and 18, are disposed in the openings 24 and are attached to yieldable members or wires 27 that are disposed in the grooves 25 and attached to the portions 20 by screws 28. The balls 26 are thus freely suspended and normally biased inwardly in the openings 24. A plunger 29, having an enlarged portion 30 of slightly-smaller diameter than the bore 21, a cam surface portion 31 and a portion 32 of relatively small diameter, is disposed in the bore 21. A plunger 33, having a shank portion 34 and a head portion 35, is disposed in the bore 21 with the head portion 35 engaging a spring 36 that extends to one end of the plunger 29. The shank 34 projects through a cap or cover plate 37 on the portion 20.

A diagonally-inclined sleeve 38, disposed adjacent to the upper end of the plate 16, serves as a bearing and support for a loosely-mounted, headed pin 39 that is prevented from withdrawal therefrom, in the closed position of the interrupter, by a cotter pin 40. The head of the pin 39 is in the path of movement of the plunger 33 of the latch 17.

A resetting device comprising lever 41, supported on the bracket 9 by a pin 42, is provided, adjacent to its free end, with an adjustable screw 43 for engagement with one end of the pin 39 and, at its pivot end, with a lug or projection 44 disposed in the path of movement of an actuating member 45 on the lever 15.

In the closed position of the interrupter, 10 as shown in Fig. 1, a transverse web portion 46 of the lever 15 holds the plunger 34 of the latch 18 against the spring 36 which, in turn, presses against the plunger 29. This assists in maintaining the enlarged portion 30 of the 15 plunger 29 in position between the balls 26 that are, thereby, held at their outer positions, partially in openings 47 in the lever 15 that register with the openings 24 in the portion 20 of the latch 18.

20 The lever 15, being biased in the counter-clockwise direction, as viewed in the drawings, by the weight of the beam 4 and the parts suspended therefrom, impinges upwardly against each of the balls 26, thus exerting a diagonal force through the balls to 25 the portion 20 at the upper edges of the openings 24. The construction and operation of the latches 17 and 18 are similar.

The smaller portion 32 of the plunger 29 30 of the latch 17 is, in the closed position of the interrupter, positioned in alignment with an actuating rod 48 of the magnet 19. When the magnet 19 is energized to actuate the rod 48 upwardly, the plunger 29 is raised to remove the portion 30 thereof from between the balls 26 which, thus released, move inwardly to release the bell-crank lever 11. This opens the interrupter, and the parts of the operating mechanism assume the positions 40 indicated in Fig. 2. In the open position of the interrupter, the plunger 33 of the latch 17 engages and presses the pin 39 in the sleeve 38 to a position against the screw 43.

An inclined channel or bore 49, below the 45 portion 20 of the latch 18, into which the portion 32 of the plunger 29 of the latch 18 projects, is adapted to receive a rod 50 having a beveled end portion 51, a cut-away portion 52 and an outer or operating end 53. A set 50 screw 54, in an upper portion 55 of the frame or casing of the magnet 19, extends into the channel 49 and, in co-operation with the rod 50, at the ends of its cut-away portion 52, prevents the withdrawal of the rod from the 55 channel.

To release the lever 15, either to manually open the interrupter or to move the lever 15 to its reset position after the interrupter has been electrically tripped, the rod 50 is pressed 60 inwardly in the channel 49. This engages the beveled portion 51 of the rod 50 and the smaller portion 32 of the plunger 29 to release the latch, as above described.

When the lever 15 is moved toward its reset 65 position, as shown in Fig. 3, the reset actu-

ing member 45 thereon engages the lug 44 on the lever 41. This turns the lever 41 in a clockwise direction to press against the pin 39, which movement depresses the plunger 33 of the latch 17 to move the plunger 29, 70 through the spring 36, to a position between the balls 26 that are, thereby, moved outwardly to latching engagement with the lever 15. When thus latched, the levers 11 and 15 may be moved downwardly to close the interrupter and to be held by the latch 18. 75

The plungers 29 thus serve as ultimate holding or key members which hold only a relatively-small portion of the main holding and latching load. This greatly facilitates 80 the operation, reduces the wear of the parts and increases the speed of operation of the interrupter.

While I have shown and described a particular form of my invention, changes may 85 be effected therein without departing from the spirit and scope thereof, as set forth in the appended claims.

I claim as my invention:

1. The combination with two members relatively movable in parallel planes, of a latching device comprising a cam member and a latching element carried by one of said members the latching element being adapted to be moved into the path of travel of the other 90 of said members, and an actuating member for the latching device adapted to operate the cam member to move the latching element into engagement with the second movable member, which second movable member 95 may be rendered inoperative upon withdrawal of the actuating member.

2. The combination with relatively movable members, of a latching device for holding 100 said members with respect to each other, a second latching device for holding both of said relatively movable members when they are latched together by said first latching device, means for releasing said latches, a resetting device for said first latching device disposed independently of all of said members and devices, and means on one of said relatively movable members for actuating said resetting device. 110

3. The combination with two relatively 115 movable members, of a pair of spherical latching members yieldingly supported by one of said members in inoperative position and a yieldingly supported camming member adapted to be passed between the spherical members to move them into the path of travel of the other movable member, a distance less than the radius of said spherical members, whereby the spherical members may be returned to inoperative position by 120 movement of the said second relatively movable member, upon withdrawal of the camming member.

4. The combination with two members relatively movable in parallel planes, of a lock- 130

- ing element yieldingly supported in inoperative position by one of said members and adapted to interlock said members in a definite relation, actuating means for moving 5 the locking element into operative position, the said actuating means being operated by relative movement of the said members into locking position.
5. The combination with two members relatively movable in parallel planes, of a locking element yieldingly supported in inoperative position by one of said members, and a cam member and actuating means carried by said member for moving the locking 10 element into operative position with respect to the other movable member, the actuating means being adapted to operate the cam member whereby, upon relative movement of the said members, the said locking element is 15 moved into inoperative position, upon withdrawal of the actuating means.
6. A latching device comprising relatively movable members one of which has an apertured portion and the other of which has a 20 bifurcated portion to embrace said apertured portion, said apertured member having auxiliary openings leading oppositely toward said bifurcated portion, a holding member 25 in each of said auxiliary openings for co-operation with said bifurcated portion, a 30 yieldable suspension member securing each of said holding members in position, a plunger having portions of different diameters and an intermediate tapered portion disposed in said apertured member between said holding members, a resilient member for biasing said plunger, a second plunger for actuating said first plunger through said resilient member and a member for moving 35 said first plunger against the action of said resilient member.
7. The combination with two relatively movable members, of a latching element yieldingly supported by one of said members in inoperative position, a cam surface 40 carried on the last said member adapted to operate the said latching element, means adjacent to the last said member to cause the said cam surface to move the latching element into operative position, actuating means on 45 the other of said members for operating the first said means when the said members are adjacent one another, and additional means operable to move the cam surface to release the said latching element after the members 50 have been moved to a predetermined position.
- In testimony whereof, I have hereunto subscribed my name this 1st day of April, 1920.

WALTER E. McCOY.
